Design for Campaign Blank

UNITED STATES PATENT OFFICE.

THOMAS ADAMS, OF HUDSON CITY, NEW JERSEY.

DESIGN FOR A CAMPAIGN-LAMP.

Specification forming part of Design No. 6,119, dated September 10, 1872.

Specification of a Design for a Campaign-Lamp, invented by THOMAS ADAMS, of Hudson City, in the county of Hudson and State of New Jersey.

The design of the shape and configuration of this lamp is represented in the drawing.

The body *a* of the lamp is shaped like the crown of a soft hat, with the wick *b* at the upper part. The base *b* of the lantern or lamp is made like the rim of a soft felt hat. The staff or handle, with or without gimbals or rings, by

which the lamp is carried, forming no part of the design, is not shown or described.

I claim as my invention—

The design of the shape of the campaign-lamp, as described.

Signed by me this 12th day of August, A. D. 1872.

THOS. ADAMS.
